UNITED STATES PATENT OFFICE.

JOHN T. SHANNON, OF CONNEAUTVILLE, PENNSYLVANIA.

RAIL-SUPPORT.

SPECIFICATION forming part of Letters Patent No. 763,640, dated June 28, 1904.

Application filed October 28, 1903. Serial No. 178,541. (No model.)

To all whom it may concern:

Be it known that I, JOHN T. SHANNON, a citizen of the United States, residing at Conneautville, in the county of Crawford and State 5 of Pennsylvania, have invented a new and useful Improvement in Rail-Supports, of which improvement the following is a specification.

This invention relates to certain new and useful improvements in rail-supports, and relates more particularly to a chair for holding the main rail and a guard-rail located adjacent thereto.

The object of this invention is to provide a chair in which the main and guard rails may 15 be secured in such a manner that the chances of accidental displacement of either of said rails will be reduced to a minimum.

A further object of this invention is to provide a chair which may be cheaply constructed and which will be efficient in holding the rails in place.

A still further object of this invention is to provide a chair in which the rails may be secured any desired distance apart and secured 25 in the said position.

With the above and other objects in view the invention consists in the novel construction, combination, and arrangement of parts to be hereinafter more fully described, and 30 specifically pointed out in the claim.

In describing the invention in detail reference is had to the accompanying drawings, forming a part of this specification, and wherein like numerals of reference indicate like parts 35 throughout both views, in which—

Figure 1 is an end elevation of my improved chair with a main and guard rail secured therein. Fig. 2 is a plan view thereof.

The reference-numeral 1 indicates the chair, 40 in which the main rail 2 and guard - rail 3 are secured, the said chair resting on and being secured to the cross-tie 4. The chair 1 may be cast; but I prefer to form the same out of a piece of sheet metal on one end of 45 which the angular ridge 5 has been formed. On the other end the said plate is bent or formed into the vertical extension 6, and in-

termidate the length of said plate the same is formed as clearly shown at 7 in Fig. 1.

The forming of the plate 1 as indicated at 50 7 forms the spaces 8 9, and the main rail 2 is adapted to be within the space 8 and be held therein by the spike 10 and the angular ridge 5. The one flange of the guard-rail is cut off and is adapted to rest in the space 9 and be 55 held therein by the track-brace 11, which is secured by the spikes 12 12. Suitable apertures are formed in the chair 1 to permit the spikes 12, 12, and 10 to pass therethrough into the tie 4. Heretofore much difficulty has 60 been experienced in securing the adjacent flanges of the two rails, and as this was the point at which the strain was on the guard-rail my device provides a means whereby the 65 guard-rail may be securely held at this joint and also permits the two rails to be located as near each other as is desirable.

While I have herein described my invention in detail, it will be obvious that various changes may be made in the proportions and 70 details of construction without departing from the general spirit of my invention.

Having fully described my invention, what I claim as new, and desire to secure by Letters Patent, is—

In a device of the character described, the combination with the main and guard rails, of a plate upon which the said rails rest, a portion in the center of said plate formed to receive the adjacent flanges of said rails, a projection formed on said plate against which one flange of one of the rails is adapted to rest, a track-brace for securing the other of 80 said rails and a projection formed on the plate adapted to prevent displacement of said track- 85 brace, substantially as described.

In testimony whereof I have hereunto signed my name in the presence of two subscribing witnesses.

JOHN T. SHANNON.

In presence of—

DAVID FITZGERALD,
IRA FETTERMAN.
